US00D769964S

(12) **United States Design Patent** (10) **Patent No.:** **US D769,964 S**
Lu (45) **Date of Patent:** **** Oct. 25, 2016**

(54) **CALCULATOR WITH WIRELESS DIGITAL KEYBOARD**

(71) Applicant: **Shenzhen Loyal Electronics Co., Ltd.**, Shenzhen (CN)

(72) Inventor: **Zhichun Lu**, Shenzhen (CN)

(73) Assignee: **SHENZHEN LOYAL ELECTRONICS CO., LTD.**, Shenzhen (CN)

(**) Term: **14 Years**

(21) Appl. No.: **29/516,291**

(22) Filed: **Jan. 30, 2015**

(30) **Foreign Application Priority Data**

Dec. 22, 2014 (CN) 2014 3 0544726

(51) **LOC (10) Cl.** **18-01**

(52) **U.S. Cl.**

(57) **CLAIM**

The ornamental design for a calculator with wireless digital keyboard, as shown and described.

DESCRIPTION

FIG. 1 is a perspective view of a calculator with wireless digital keyboard in accordance with the present invention;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1; and,

FIG. 7 is a bottom view of FIG. 1.

The broken lines in FIG. 4 depict parts of the calculator with wireless digital keyboard that form no part of the claimed design.

1 Claim, 4 Drawing Sheets
